BOOK SUPPORT FOR HOLDING A BOOK IN OPEN POSITION

Morton S. Pearl, 1940 Bay Drive,
Miami Beach, Fla. 33141

Filed Mar. 4, 1970, Ser. No. 21,740

Term of patent 14 years

Int. Cl. D6—99

U.S. Cl. D33—3

FIG. 1 is a right hand perspective view of a book support for holding a book in open position, showing my new design.

FIG. 2 is a left hand perspective view thereof.

I claim:

The ornamental design for a book support for holding a book in open position, as shown.
